UNITED STATES PATENT OFFICE

2,534,281

PRESSER FOOT FOR SEWING MACHINES

Jose L. Luna, Houston, Tex.

Application February 18, 1948, Serial No. 9,312

1 Claim. (Cl. 112—235)

1

This invention relates to sewing machine attachments, and more particularly to a presser foot for a sewing machine.

An object of the invention is to provide a presser foot having a plurality of angularly directed channels therein adjacent to the aperture which is provided in the foot, for the passage therethrough of the conventional sewing machine needle.

Another object of the invention is to provide a device of this character whereby decorative material such as cord or ribbon or the like may be quickly and easily sewed to fabrics in one or more layers.

A further object of the invention is to provide a device of this character that is simple in construction, inexpensive to manufacture and efficient in operation.

With the above and other objects in view, the invention consists of the novel details of construction, arrangement and combination of parts more fully hereinafter described, claimed and illustrated in the accompanying drawing in which:

Figure 1 is an elevational view of an embodiment of the invention in use with a sewing machine;

Figure 2 is a side elevational device of the embodiment, per se;

Figure 3 is a plan view of the embodiment with the presser foot bar shown in section;

Figure 4 is a front view of the embodiment and

Figure 5 is a sectional view on the line 5—5 of Figure 3.

Referring more in detail to the drawing, the reference numeral 10 designates the presser foot constructed in accordance with the invention.

The presser foot 10 is provided with a U-shaped portion 11, which is adapted to engage and be mounted on the presser foot bar 12. A set screw 13, carried by the bar enters the slot 14 in the portion 11, whereby the presser foot is attached to the bar 12 in fixed relation thereto. The presser bar 12 is conventional with sewing machines of the usual structure indicated in Figure 1 by the numeral 15.

The foot member 16 of the presser foot 10 is somewhat offset in relation to the portion 11, and is provided with the aperture 17 for the reception of the sewing machine needle 18. The foot member 16 is generally curved in formation and the base is provided with the guide slot 19 which communicates with the aperture 17. The needle 18 carries in its eye the thread 20 which is usually supplied from a spool 21 on the spindle 22 on the machine 15.

2

Forwardly of the aperture 17, and slightly removed therefrom, is an angularly directed aperture 23, which communicating with the slot 19, is adapted to feed a decorative cord 24 to the slot below the needle 18. Forwardly of, and slightly removed from the aperture 23, is the angularly directed slot 25 which also communicates with the slot 19, and is adapted to feed a decorative ribbon 26 to the slot 19 below the cord 24. Forwardly of and slightly removed from the slot 25, is a second angularly directed slot 27 which communicates with the slot 19 at its forward end. The slot 27 is wider than the slot 25, and is adapted to feed a larger decorative ribbon 28 below the narrower ribbon 26. To provide for the width of the ribbon 28, the foot member 16 is provided with a wider slot 30 formed by the oppositely inset opposed shoulders 31 and 31' respectively. The slot 30 underlies the slot 19 so that as the cord 24 and ribbon 26 are guided through slot 19, the ribbon 28 is guided through slot 30.

In operation, when it is desired to decorate the surface of some material with a layer of decorative cord and ribbons, it is only necessary to thread the ribbon 28 through the slot 27 into guide slot 30, until it is below the needle 18, then thread the ribbon 26 through the slot 25 until it is below the needle 18, in guide slot 19 and overlying the ribbon 28. The cord 24 is then threaded through the opening 23 until it is below the needle 18 and overlying the ribbon 26, in guide slot 19. Then when the presser foot 10 is released, it will hold the cord and ribbons in place. Subsequent operation of the machine 15 in the conventional manner will then cause the needle to stitch the respective layers to the material 29, as shown in Figure 2. The thread 20 stitches the respective layers to the material in the usual manner.

It is believed that from the foregoing description, the construction and operation of the invention will be apparent to those skilled in the art, and it is to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

A presser foot for a sewing machine, comprising an attaching portion and a foot portion, an aperture in said foot portion to receive the needle of a sewing machine, an angularly directed aper-

ture in the foot portion forwardly of said first aperture, an angularly directed slot whose longitudinal length is greater than the radius of the second aperture in the foot portion forwardly of said second aperture, a second angularly directed slot whose longitudinal length is greater than the length of the first slot in the foot portion forwardly of said first slot and said slots adapted to extend transversely of said foot portion, oppositely disposed shoulders on the opposite curved edges of the bottom surface of said foot portion providing a slot extending longitudinally of the foot portion, a second set of oppositely disposed shoulders inwardly of the said first shoulders and on a higher plane than said first shoulders providing a slot of less width than said first slot and said aperture and said first slot

connected with the slots in the bottom surface of said foot portion.
